UNITED STATES PATENT OFFICE.

LOUIS COTÉ, OF SAINT HYACINTHE, CANADA.

IMPROVEMENT IN MACHINES FOR TRIMMING AND BURNISHING THE SOLES OF BOOTS AND SHOES.

Specification forming part of Letters Patent No. 135,694, dated February 11, 1873.

To all whom it may concern:

Be it known that I, LOUIS COTÉ, of Saint Hyacinthe, of the Province of Quebec, of the Dominion of Canada, have invented a new and useful Improvement in Machinery for Trimming or Burnishing the Edge of a Sole or that of the Heel thereof, as circumstances may require; and I do hereby declare the same to be fully described in the following specification and represented in the accompanying drawing, of which—

Figure 1 is a side elevation, and Fig. 2 a vertical and longitudinal section, of my machine. Fig. 3 is a side view, and Fig. 4 an end view, of its burnishing-sleeve. Fig. 5 is a side view, and Fig. 6 is an end view, of its cutting or rasping sleeve.

The first part of my invention relates to a separate rasping or burnishing sleeve, a clamping-guide, and an arbor, all being arranged, constructed, and combined substantially as hereinafter described, and as represented in the drawing. The second part of the invention relates to an adjustable gage, its operative screw, and fork, arranged and combined with the rasping or burnishing sleeve, the guide, and the arbor, all in manner and to operate essentially as specified. The third part of my invention relates to the adjustable gage provided with recesses to receive the teeth of the rasping or burnishing sleeve, in order to prevent such sleeve from revolving on and independently of the arbor so as to revolve the clamp-guide and loosen the screw thereof.

In the drawing, A denotes an arbor or shaft furnished with a pair of fast and loose pulleys, *a b*, and supported in boxes *c d* upheld by a suitable frame, B. The arbor projects beyond one end of the frame, and at or near its outer end is turned down to a shoulder, *e*, to receive upon the part *f* so reduced the burnishing or rasping sleeve C, which encompasses such part *f* and rests at one end against the shoulder *e*. The sleeve C is a short tube of steel, having either rasping or cutting or burnishing teeth or projections upon its outer surface or periphery. The clamping-guide D, shown in end views in Figs. 7 and 8, in side view in Fig. 10, and in longitudinal section in Fig. 9, is inserted in and fitted to the bore of the sleeve C without extending quite to the adjacent end of the arbor, a clamp-screw, *g*, ar-

ranged in the bore of the guide D and screwed into the arbor, serving to hold the guide, and by means of it the sleeve, to the arbor, so as to be revolved by it when it may be in revolution. This method of making the sleeve C and the clamping-guide D admits of the ready removal of either from the arbor for repair, or for the substitution of others of like kind as occasion may require. Furthermore, there is upon the arbor and encompassing it another sleeve or adjustable gage, E, it being a tube fitted to slide upon the arbor and the sleeve C, lengthwise thereof. A stud, *h*, extends from the gage E into a short groove, *i*, made in the arbor longitudinally, the same causing the gage E to revolve with the arbor. The gage E is also grooved transversely to receive a fork, *k*, pivoted to a screw, *l*, screwed into and through a projection, *m*, elevated on or making part of the frame.

On revolving the screw the gage may be moved either nearer to or further from the annular lip *n* of the clamping-guide, as the thickness of a sole to be trimmed or burnished on its edge may require, and this while the machine may be in operation.

In order to relieve the clamp-screw from any tendency to be unscrewed from the arbor by the rasping or burnishing sleeve while in revolution and pressed against a sole, the gage E is formed with recesses *o* arranged with respect to its bore, as shown in end view of it in Fig. 11. The sleeve-teeth or burnishing-projections, extending into these receivers, will cause the sleeve to revolve with the gage and the arbor. Thus it will be seen that whichever way the arbor may be revolved there will be no tendency of the sleeve to revolve the clamp-guide so as to loosen the clamp-screw. The gage, therefore, besides performing the function of a gage, serves another purpose, as explained.

This little machine has been found to be of great advantage or utility. By the arrangement of the gage E, the rasping or burnishing sleeve, and the guide together, and so as to extend on the arbor beyond one end of the frame in manner as shown, a workman can readily present to them a shoe or boot to be trimmed or burnished on its sole-edge, and, while holding it, can turn it or move it as may be necessary to effect the proper reduction or

burnishing of its edge, the guide-lip *n* being at the time inserted in the groove or space between the sole and the upper.

I make no claim to the burnishing-machine described in the United States Patent No. 127,904, in which two or more different "setting-tools" are employed, one being for the shank-edge and the other being for the thicker parts of a sole.

In my machine I make use of but one burnishing-tool with an adjustable gage. Furthermore, there is in the said patented machine no separate rasping or burnishing sleeve and a clamping guide like the sleeve *C* and guide *D* as in my machine.

By having the sleeve *C* separate, as de-

scribed, it may be removed and another of greater or less length may be substituted, or a new one be readily applied in its place when it may be worn or unserviceable; therefore

I claim as my invention as follows, viz:

The adjustable gage *E*, provided with the recesses *o* or the equivalent thereof, in combination and arranged with the rasping or burnishing-sleeve *C*, the clamping-guide *D*, arbor *A*, and clamp-screw, all substantially as specified.

LOUIS COTÉ.
